UNITED STATES PATENT OFFICE.

WILLIAM J. SCHLACKS, OF CHICAGO, ILLINOIS, ASSIGNOR, BY MESNE ASSIGNMENTS, TO LOCOMOTIVE LUBRICATOR COMPANY, OF CHICAGO, ILLINOIS, A CORPORATION OF DELAWARE.

LUBRICATING SYSTEM FOR LOCOMOTIVES.

Application filed March 2, 1923. Serial No. 622,398.

This invention relates to lubrication and is preferably directed to the efficient lubrication of locomotive cylinders and valve chambers. In the lubrication of these

- 5 parts, as heretofore practiced, the oil is forced by the hydrostatic or force feed systems into the steam inlet pipe which supplies steam to the valve chambers and cylinders, the oil being carried into the parts by
 10 the current of steam. With such practice, when the engine is drifting, there is no means for conveying the oil from the said steam pipe to the cylinders as the supply of steam is then shut off. This has resulted
 15 in inefficient lubrication on mountain railroads where a great deal of drifting is done and has also caused trouble when the enginemen shut off steam for a considerable distance in approaching a stop.
 20 It is an object of this invention, therefore, to provide means for delivering oil to the cylinders when the locomotive is drifting, as well as when the locomotive is running with steam.
 25 It is a further object of the invention to provide pressure control valves delivering to both the inlet steam pipe and the cylinder, which valves are so controlled that when the steam supply in the cylinders is
 30 shut off, or the steam in the steam inlet pipe or cylinders drops below a certain pressure, the valve delivering to the cylinder will begin to function, the valve at other times remaining inoperative and the valve in the
 35 steam inlet pipe being operative.

It is more specifically an object of the invention to provide valves, as above specified, which have pressure controlled means for closing and opening the same, the valve
 40 delivering to the inlet steam pipe having a conduit leading thereto from the oil supply means and a conduit leading therefrom beneath the pressure means, the latter conduit being connected to the valve delivering to
 45 the cylinder below the pressure means therein and to further provide a conduit leading from the steam inlet pipe or the end of the cylinder to the valve delivering to the cylinder, which conduit is connected to the
 50 latter valve above the pressure means therein.

These and other objects and advantages of the invention will be fully set forth in the following description made in connec-

tion with the accompanying drawings in 55 which like reference characters refer to the same parts throughout the different views and in which,

Fig. 1 is a view in front elevation of a 60 portion of a locomotive showing the cylinder saddle, the steam inlet pipes and cylinders with the device of the invention applied thereto;

Fig. 2 is a view in side elevation of the 65 front portion of the locomotive showing the invention applied thereto;

Fig. 3 is a vertical section of the check valve used in the steam inlet pipe;

Fig. 4 is a vertical section through the 70 check valve used in the cylinder, said valves being shown on an enlarged scale;

Fig. 5 is a fragmentary view similar to Fig. 2, showing a modification; and

Fig. 6 is a fragmentary view similar to 75 Fig. 1, showing a modification.

The lubricating system illustrated is known as the Schlacks force feed lubrication and this system uses an oil pump for delivering oil, such as shown in Patent No. 822,684, granted to John F. McCanna, 80 of date, June 5th, 1906.

In this system also the oil is forced into the steam containing portions through pressure controlled check valves.

Referring to the drawings, a portion of 85 a locomotive is shown comprising the cylinder saddle 1 having therein the cylinders 2 to which deliver the steam inlet pipes 3. While the pipes 3 lead from the boiler the pressure in said pipes is determined by the 90 throttle (not shown) interposed in said pipes. It may be mentioned that the type of locomotive shown is a simple type in which the valve chambers 4 are disposed above the cylinders which, in turn, deliver 95 steam to the cylinders 2.

In Fig. 2, the cross head 5 to which the piston rod 6 is connected is shown and a lever 7 is connected to the cross head having a connection at its upper end connected by 100 a link 8 to the operating arm 9 of the oil force feed means or pump 10. In the system noted, the oil in such a pump is usually heated by steam, for which purpose conductors illustrated as 11 are provided. The 105 pump 10 is of the type comprising a plurality of high pressure plungers which deliver the oil to the conduits 12, which con-

duits are connected to the check valves 13 to be later described, carried by and delivering to the steam inlet pipes 3. Check valves or pressure control valves 15 to be later described, are connected to and adapted to deliver to the cylinders 2. The valves 15 have connected thereto beneath the pressure means therein conduits 14 which are connected to the pressure oil supply means and in the embodiment of the invention illustrated are shown as connected to the valves 13 beneath the pressure means therein. A conduit 16 is connected at one end to the live steam passage to the cylinders and is shown connected to the steam inlet pipe 3 and is connected at its other end to the valve 15 and is connected to and delivers thereto in the top of the bonnet of the valve above the pressure means therein.

The valve 13 comprises the base portion 17 having a threaded cylindrical portion 18 adapted to be screwed into the member to which the oil is delivered which, in the present case, is the steam inlet pipe 3. A central opening 19 is formed in this valve which, at its upper end, receives the valve seat 20 with which co-operates the pin valve 21. The upper portion or bonnet of the valve comprises a cylindrical casing 22 which is threaded and tightly fitted in the base portion 17. A pressure diaphragm 23 is fitted into bowl portion 17 and is clamped against leakage on its outer circumference by washer 24 and the gasket shelf or shoulder in bowl portion 17. The washer 24 is clamped against diaphragm 23 by bonnet 22 screwing into bowl portion 17. The member 23 has a shouldered upper end engaging and positioning spring 25 and its lower shouldered end which is disposed centrally in washer 24 has a central recess therein with the top of which contacts the top of the pin valve 21, said valve being held in place and guided by the member 24 threaded into the bottom of the spring seat 23, members 24 and 23, thus centrally clamping diaphragm 23. The pressure spring 25 through its seat 23 contacts the spring seat 23 and is placed under pressure and adjusted as to pressure by the spring adjusting nut 26 which is threaded into the top of the member 22 and contacts with the plug 27 seated in the top of the spring 25. The base member 17 is provided with two passages 28 and 29, one of which leads from each side of the oil chamber 30 of the valve. Passages 28 and 29 lead through projections on the base member 17 with which are connected the conduits 12 and 14 by means of threaded unions 31 of a well known type.

The valve 15 comprises the base member 32 having the threaded attaching end 33, a valve seat 34 and the pin valve 35 which are substantially the same as described in

connection with valve 13. A bonnet or casing 36 is also threaded into the base member 32 in which slides the spring seat 37 having therein the member 38. A diaphragm 37 is held in place by a washer 38 and is centrally clamped between members 37 and 38. The casing 36 contains the pressure spring 39, spring adjusting nut 40 and plug 41, all of which parts, except the casing 36 and bowl 32, are identical with the parts described in the valve 13. The casing 36, it will be noted, has an imperforate wall and a projection 42 extends therefrom above the diaphragm 37 through which leads the passage 43 communicating with the conduit 16 which is connected to the projection 42 by the threaded coupling sleeve 44 and member 45 in a well known manner, as illustrated in Fig. 4. The member 32 has one lateral projection through which extends a passage 46 communicating with conduit 14, the latter being coupled to said projection by members 47 and 48.

With the parts described, disposed and arranged as shown and above described, the valves 13 have their springs 25 adjusted, for instance, so that the valves will open or release at a pressure of 225 pounds per square inch. This is on the assumption that the working steam pressure of the locomotive is 175 pounds per square inch. The springs in the valve 15 will, however, be set to release or open at 175 pounds per square inch pressure. It will now be noted that steam from the inlet pipe 3 at 175 pounds pressure will be delivered to the top of the diaphragm 37 of valve 15 by the conduit 16 so that in addition to the spring pressure of 175 pounds per square inch on the diaphragm 37, there will also be a steam pressure of like amount so that there will be a total pressure per square inch on the diaphragm 37 of 350 pounds so that it will take a pressure in excess of 350 pounds to lift the diaphragm and open valve 35 to permit oil to pass through the member 33 into the cylinder. When the locomotive is running under steam, the conditions will be as above stated and the oil will be pumped by the pump 10 to the valves 13 and this oil will be delivered into the steam inlet pipe 3 since the valves 13 will open or release at 225 pounds pressure, while it takes 350 pounds pressure or more to open the valves 15. When the engine is running under steam, therefore, no oil will be delivered through the valves 15 but all of the oil will be delivered through the valves 13 into the steam inlet pipe and this oil will be carried by the steam into the cylinders 2 and the valve chambers 4. When the engineer shuts off the steam to the cylinders and the locomotive drifts, the 175 pounds per square inch pressure on the top of the diaphragms 37 is removed leaving 130

only the spring pressure of 175 pounds thereon. The oil pumped to the valve 13 through conduit 12 will now pass out from said valve through the passage 29 and the conduit 14 and will flow to the valve 15 and lift this valve and will thus be delivered into the cylinder. There being but 175 pounds pressure to overcome on the valve 15, this valve will be open and the valve 13 requiring 225 pounds pressure will remain closed, the oil, of course, taking the path of least resistance. When the locomotive is drifting, therefore, the oil will simply by-pass through the valves 13 and will be delivered to valves 15. It will, of course, be understood, that the pressure of the springs on the diaphragms of the valves 13 and 15 will be adjusted in accordance with the steam pressure used, the figures given above being suitable for the assumed 174 pounds per square inch steam pressure.

In the modification shown in Figs. 5 and 6, the valves 13 and 15 are placed in the steam pipe 3 and the cylinder 2 just as in the structure shown in Figs. 1 and 2 and the valve 13 has communicating therewith below the pressure element therein the conduit 12 leading to the oil pressure means 10. The conduit 14 also leads from the oil supply conduit as through the valve 13 below the pressure element therein, to the valve 15 below the pressure element in the latter. Instead, however, of having the conduit 16 leading to the steam pipe 3 from the valve 15 a conduit 50 leads from the valve 15 above the pressure element therein to the rear end of the cylinder 2. With the oil pump shown, the pressure plungers thereof operate only on the clockwise stroke of the operating arm 9, the pump being operated by a ratchet so that the pump is only operated when the piston moves from the back end of the cylinder to the front end thereof.

With the arrangement shown in Fig. 4, assuming 175 pounds pressure of steam used in the locomotive, the valve 13 will be adjusted to release at 225 pounds pressure per square inch and the valve 15 will be adjusted to release at 75 pounds pressure per square inch. Now when the steam is first admitted to the cylinder 2 and before the valve cuts off the steam there will be a pressure of approximately 175 pounds in the end of said cylinder. This pressure will be added to the 75 pounds pressure already on the valve 15 owing to the conduit 50 so that said valve will have thereon a total pressure of 250 pounds. During the first portion of the stroke of the piston therefore and the corresponding stroke of the pump plungers, the oil will be discharged into the steam inlet pipe 3 from the valve 13 which will open at 225 pounds. After the steam is cut off in the steam cylinder 2 the same will expand and the pressure therein will fall. When

the pressure in the cylinder falls below 150 pounds, the pressure on the valve 15 will be less than the pressure on the valve 13 and the oil forced through the conduit 12 will thus by-pass the valve 13 and go through the conduit 14 and into the cylinder through the valve 15. Thus on one stroke of the piston, oil is discharged into both the steam pipe 3 and the cylinder 2. This operation occurs when the engine is running with steam. When the steam is shut off by the throttle and the locomotive is drifting all of the oil will be injected into the cylinder 2 through the valve 15 in the embodiment shown in Figs. 1 and 2.

From the above description it is seen that applicant has provided a very simple and efficient means by which the cylinders will be very efficiently lubricated while the locomotive is drifting and no steam is being supplied to the cylinders. The invention requires but very little change in the standard locomotive system and but a small modification in the check valves for pressure valves used. It will be noted that with the figures given in the above illustration, the valves 13 will cease delivering oil into the steam pipe whenever the pressure therein is less than 50 pounds per square inch. The action of the device is entirely automatic and the oil is efficiently distributed both when the locomotive is running under steam and when the same is drifting.

It will, of course, be understood that various changes may be made in the form, details and arrangement of the parts without departing from the scope of applicant's invention, which, generally stated, consists in the matter shown and described and set forth in the appended claims.

What is claimed is:

1. In combination with a locomotive cylinder and a steam inlet pipe to said cylinder, a conduit for oil under pressure, normally seated valves controlling the delivery of oil from said conduit to the inlet pipe and cylinder respectively, mechanical means for holding said valves seated differentially adjusted as to pressure so that the valve admitting oil to the cylinder will open at less pressure than the valve admitting oil to the inlet pipe and steam actuated means capable of being connected to the inlet pipe acting under full steam pressure to hold the cylinder valve to its seat with greater pressure than that acting to seat the inlet pipe valve.

2. The combination with the cylinder of a locomotive and the steam inlet pipe thereof, of a pressure controlled valve communicating with said inlet pipe and a pressure controlled valve communicating with said cylinder, means for delivering oil under pressure, an oil conduit leading therefrom to said first mentioned valve, a conduit leading from said first mentioned valve to said second men-

tioned valve, and a steam conduit leading from said steam inlet pipe to said second mentioned valve to place steam pressure thereon resisting opening of said valve, said first mentioned valve being set to open at a pressure less than the pressure at which the second mentioned valve is set to open plus the steam pressure and said second mentioned valve being set to open in the absence of steam pressure at a pressure considerably less than said first mentioned valve.

3. The combination with the cylinder of a locomotive and the steam inlet pipe thereof, of a check valve connected to said pipe, said valve having a spring pressed diaphragm tending to hold it in closed position, a check valve having a spring pressed diaphragm connected with said cylinder, means for delivering oil under pressure, an oil conduit leading therefrom to said first mentioned valve delivering thereto beneath its diaphragm, a conduit leading from beneath the diaphragm of said first mentioned valve to said second mentioned valve and connected to the latter beneath its diaphragm, and a steam conduit leading from said steam inlet pipe to said second mentioned valve and connected thereto above the diaphragm therein, said valves being differentially adjusted in accordance with the steam pressure.

4. The combination with the cylinder of a locomotive and steam inlet pipe thereof, of a check valve in and communicating with said steam inlet pipe, said valve having a diaphragm therein and a pressure spring above the diaphragm tending to hold the valve in closed position, a check valve connected to and delivering to said cylinder said valve having a diaphragm therein and a pressure spring above the diaphragm tending to hold the valve in closed position, means for delivering oil under pressure to said first mentioned valve beneath the diaphragm thereof, a conduit leading from beneath said diaphragm to said second mentioned valve and delivering to the latter beneath the diaphragm thereof, a conduit

leading from said steam inlet pipe to said second mentioned valve and connected to the same above the diaphragm thereof, said valves being differentially adjusted in accordance with the steam pressure whereby when the steam is above a certain pressure in the inlet pipe oil will be delivered into said pipe through said first mentioned valve but when the steam pressure falls below said point, such delivery of oil will be discontinued and oil will be delivered into the cylinder through said second mentioned valve.

5. In combination with the steam cylinder of a locomotive and the steam inlet passage thereto, a valve communicating with said cylinder having a pressure means therein, a valve communicating with said steam inlet passage and having a pressure means therein, said valves being differentially adjusted, a conduit leading to a force feed oil supply and connected to said last mentioned valve below said pressure means therein, a conduit leading from said last mentioned valve below said pressure means and communicating with said first mentioned valve below the pressure means therein, and a conduit connected to said first mentioned valve above the pressure means therein and communicating with a source of steam pressure of the locomotive.

6. The combination with the cylinder and steam inlet pipe of a locomotive, of a pressure valve communicating with said steam inlet pipe, a pressure valve communicating with said cylinder, means for supplying oil under pressure, conduits connecting said means, valves and cylinder, said valve being differentially adjusted whereby under a certain pressure the valve in the steam inlet pipe will open and oil will be supplied therethrough into said pipe, and under a reduced pressure the valve in the cylinder will open while the valve in the steam inlet pipe remains closed and oil will be fed to said cylinder.

In testimony whereof I affix my signature.
WILLIAM J. SCHLACKS.
